Inventor

Peter M. Christensen,

By Clarence O'Brien.

Attorney

UNITED STATES PATENT OFFICE

PETER M. CHRISTENSEN, OF EXIRA, IOWA

WIRE FASTENER FOR FENCE POSTS

Application filed January 9, 1930. Serial No. 419,631.

This invention relates to fastening devices, and has more particular reference to a fastening device adaptable for use on fence posts securing the wires of the fence in the notches 5 provided therefor in the fence posts.

The present invention further relates to new and novel improvements in such types of fastening devices as forms the subject matter of my copending application, Serial 10 No. 403,836, filed by me under date of October 31, 1929.

Other objects and advantages of the present invention will become apparent during a study of the following description, taken in 15 connection with the accompanying drawings, wherein:

Figure 1 is a fragmentary side elevation of a fence post equipped with my improved wire fastening device,

20 Figure 2 is a front elevational view thereof,

Figure 3 is a top plan view thereof,

Referring in detail to the drawings, it will be seen that I have designated the fence 25 post generally by the reference character 5.

The fence post 5 may be formed of metal or any other suitable material and as herein shown is preferably of angle iron structure.

One flange of the fence post is provided 30 with a plurality of vertically spaced downwardly and inwardly inclined wire receiving notches 6, said notches 6 inclining downwardly and inwardly from the longitudinal forward edge of the said one flange as clearly shown.

As contemplated by the present invention, the fastening device for retaining the wires in their respective notches 6 are formed from a single length of wire so shaped as to pro-

40 vide an intermediate portion constituting an axle 7 journaled transversely through an opening 8 provided therefor inwardly from the forward edge of said one flange of the fence post and slightly above the open end

45 of the notch as clearly shown to advantage in Figure 1.

The wire of the fastener at one end of the axle portion 7 is so shaped as to provide a substantially U-shaped portion 9, one leg 10 of which U-shaped portion at its free end

merges into the said one end of the axle portion 7, and as shown to advantage in the drawings, the U-shaped portion 9 is disposed on that side of the said one flange A of the fence post 5, opposite to the side from which 55 the flange D of the fence post projects.

As shown, the crown portion of the U-shaped part 9 is disposed rearwardly at the forward end portion of the other leg 11 of the U-shaped part 9 is adapted to extend 60 across the notch 6 above the inner end of the notch as shown in dotted lines in Figure 1.

The wire forming said fastening device, on the other end of the axle part 7 has their axle part merging into an arcuate portion 12, 65 which arcuate portion 12 in normal position extends vertically across the open end of the notch 6, and at its lower end merges into an upwardly and rearwardly inclined extended portion 13, which portion 13 at its upper end 70 is bent upon itself to provide the portion 14 extending in parallelism to the upper rear end portion of the part 13, said portion 14 extending into an offset end 15 constituting a handle for the fastener.

The device in normal wire confining position is disposed in that position shown in Figure 1 with the arcuate portion 12 extending across the open end of the notch 6, the forward end of the leg 11 of the U-shaped part 9 also extending across the notch 6, and the lower end portion of the extension 13 likewise disposed across the notch 6 for confining the wire within the inner end of the notch, while the upper end of the extended portion 13 at its end 16 abuts the flange B of the fence post and acting as a stop to limit the rotation of the fastener in one direction and thus retaining the several parts above noted of the fastener in their wire confining position relative to the notch 6.

Manifestly, to remove the fence wire from the notch 6, the fastener is rotated upon its axle part 7 to the left in Figure 1 thus drawing the parts 13, 12 and 11 from across the 95 notch 6.

It is thought that from the foregoing description, taken with the accompanying drawings, and the simplicity of the device, that a clear understanding of the construction, util-

ity and advantages of a wire fastener of this character will be had by those skilled in the art without a more detailed description.

Even though I have herein shown and described the preferred embodiment of my invention, it is to be understood that the same is susceptible to changes, comprehended by the spirit of the invention as herein described, and the scope of the appended claims.

Having thus described my invention, what I wish to claim as new is:

1. A wire fastener for use with a fence post having a wire receiving notch formed therein, said fastener formed from a single strand of wire having an intermediate portion thereof extending through an opening in the post above said notch, one end portion of said wire being bent at substantially right angles to the intermediate portion of said wire for disposition across said notch, on one side of the fence post, and at its opposite end being bent at right angles to said intermediate portion to provide a fence wire retaining part adapted to extend across said notch on the opposite sides of said fence post, said intermediate portion of the wire providing a pivot for the fastening device.

2. In a fastening device of the class described, and in combination, a fence post having an obliquely disposed fence wire receiving notch formed therein, a retaining member for retaining the wire in said notch, said retaining member being formed of a single strand of material having an intermediate portion thereof extending through an opening formed in said fence post above the open end of said notch, and said wire at one side of said fence post having said intermediate portion merging into substantially U-shape portion one leg of which is adapted to extend across said notch when said fastener is in wire retaining position, said material having said intermediate portion at the other side of said fence post merging into a right angularly disposed arcuate portion for disposition across the open end of said notch, said arcuate portion in turn merging into an upwardly and rearwardly inclined extended end portion adapted to engage said fence post for limiting the swinging movement of said fastening device when the latter is in a wire retaining position.

3. In a fastening device of the class described, and in combination, a fence post having an obliquely disposed fence wire receiving notch formed therein, a retaining member for retaining the wire in said notch, said retaining member being formed of a single strand of material having an intermediate portion thereof extending through an opening formed in said fence post above the open end of said notch, and said wire at one side of said fence post having said intermediate portion merging into a substantially U-shaped portion one leg of which is adapted to extend across said notch when said fastener is in wire

retaining position, said material having said intermediate portion at the other side of said fence post merging into a right angularly disposed arcuate portion for disposition across the open end of said notch, said arcuate portion in turn merging into an upwardly and rearwardly inclined extended end portion adapted to engage said fence post for limiting the swinging movement of said fastening device when the latter is in a wire retaining position, and said upwardly and rearwardly inclined portion of said wire being bent upon itself and terminating in a downwardly and forwardly inclined offset portion to provide a handle for said fastener.

In testimony whereof I affix my signature.

PETER M. CHRISTENSEN.
